FEEDING DEVICE FOR ROLL-GRINDING MACHINES.

1,210,936.

Specification of Letters Patent. Patented Jan. 3, 1917.

Application filed March 6, 1915. Serial No. 12,526.

To all whom it may concern:

Be it known that I, LEWIS R. HEIM, a citizen of the United States, residing at Danbury, county of Fairfield, State of Connecticut, have invented an Improvement in Feeding Devices for Roll-Grinding Machines, of which the following is a specification.

This invention has for its object to provide a simple, inexpensive and durable feeding device especially adapted for use in connection with the type of roll grinding machines forming the subject of my application for Letters Patent, Serial No. 12,524, filed of even date herewith, which will conduct the rolls to the grinding and regulating wheels and will support them while being operated upon, and in which the only part subjected to appreciable wear may be turned a number of times and then reversed to provide new wearing surfaces at an expense so trifling as to be negligible.

With the above and other objects in view I have devised the novel roll feeding device which I will now describe, referring to the accompanying drawing forming a part of this specification and using reference characters to indicate the several parts:—

Figure 1 is an elevation of my novel feeding device, one of the operative wheels appearing in elevation; Fig. 2 a plan view showing both of the operative wheels, and Fig. 3 is a section on an enlarged scale of the roll carrier on the line 3—3 in Fig. 1, looking in the direction of the arrows.

In the type of machines forming the subject of my said application referred to, the grinding operation is effected by passing the rolls between the faces of grinding and regulating wheels. The grinding wheel, rotating at a relatively high speed, acts to hold the rolls down upon the carrier and grind them, and the regulating wheel, rotating in the opposite direction at a relatively low speed, acts to cause constant and uniform rotation of the rolls while being operated upon, but at a much lower surface speed than the grinding wheel, thereby insuring that the rolls be ground to perfectly cylindrical form and avoiding the possibility of flat faces.

10 denotes the grinding wheel and 11 a wheel which I term the regulating wheel, as it regulates the speed at which the roll is rotated while being operated upon.

55 My novel feeding device is constructed as

follows: 12 denotes a block or body shown as substantially in the form of an inverted L, which is adapted to be bolted or otherwise secured to an adjustable standard, not shown, or to any suitable portion of a grinding machine.

13 denotes the carrier which is a bar lying in a slot 14 in the body. The carrier is shown as pivoted between ears 15 on the body to enable it to be swung in the vertical plane in order to give to it the most convenient degree of inclination in feeding the rolls to be operated upon to the grinding and regulating wheels. The carrier is shown as locked at the required degree of inclination by a set screw 16.

17 denotes guides ordinarily made of sheet metal which are secured to the body by screws 18 on opposite sides of the carrier. The guides are shown as provided with flanges 19, made conveniently flaring at their outer ends, between which the rolls are placed, resting upon the carrier. The guides are preferably provided with slots 20 through which the screws pass, so as to permit adjustment of the guides toward or from each other.

It will of course be obvious that the wear upon the carrier will be at the forward end thereof, that is, the portion which supports the rolls and upon which they are rotated during the grinding operation. In order to reduce the expense caused by this wear, to the minimum, I provide the upper edge of the carrier with a groove 21 which receives a hardened wearing strip 22. This wearing strip is preferably made rectangular in cross-section so as to provide four wearing surfaces, each of which may be used until a groove is worn therein, when the strip is given a quarter turn and a new wearing surface provided. When the four wearing surfaces at one end of the strip have each been used as long as practicable, four new wearing surfaces are provided by changing ends with the strip.

In practice the grinding and regulating wheels are set slightly obliquely to each other, ordinary ring-shaped wheels being used. The carrier lies between the operative wheels on the side where their faces come into closest proximity and extends past the inner edges of the operative surfaces.

23 denotes a U-shaped trough secured to

the inner end of the carrier into which the rolls drop after passing the inner edges of the surfaces of the operative wheels and by which they are conducted outward between the faces of the wheels on the opposite side of the center, which on that side lie at a greater distance apart, as clearly shown in Fig. 2.

The operation is as follows: The rolls to be operated upon are placed upon the carrier between the guides either mechanically or manually and are fed forward. As soon as a roll is picked up by the operative wheels it is drawn forward thereby, being rotated upon the carrier, and at the same time drawn forward toward the open center of the wheels. As soon as the grinding operation is completed the rolls pass from the carrier to the trough and out between the faces of the grinding and regulating wheels on the opposite side of the center, as clearly shown.

Having thus described my invention I claim:

1. A roll feeding device for grinding machines comprising a slotted body, a carrier pivoted in the slot and adjustable guides secured to the body on opposite sides of the slot.

2. A roll feeding device for grinding machines comprising a carrier by which the rolls are conducted to a position to be operated upon and by which they are carried past the operative surfaces and a trough

secured to the inner end of the carrier by which the ground rolls are conducted away from the operative surfaces.

3. A roll feeding device for grinding machines comprising a carrier by which the rolls are conducted to a position to be operated upon and by which they are carried past the operative surfaces, a wearing strip in said carrier, and a trough secured to the inner end of the carrier by which the ground rolls are conducted away from the operative surfaces.

4. A roll feeding device for grinding machines comprising a slotted body, a carrier pivoted in the slot, said carrier being provided with a groove, and a removable wearing strip in said groove having a plurality of faces which may be used successively.

5. A roll feeding device for grinding machines comprising a body having a slot, a carrier pivoted in said slot to swing in the vertical plane and means for locking the carrier at any required adjustment.

6. A roll feeding device for grinding machines comprising a body, a carrier and a removable wearing strip in the carrier having a plurality of wearing surfaces.

In testimony whereof I affix my signature in presence of two witnesses.

LEWIS R. HEIM.
